DESIGN FOR A JAR

Olbert C. Noble, Washington, Pa., assignor to Tygart Valley Glass Company, Washington,
Pa., a corporation of West Virginia

Application October 25, 1938, Serial No. 80,663

Term of patent 7 years

To all whom it may concern:

Be it known that I, Olbert C. Noble, a citizen of the United States, residing at Washington, in the county of Washington, State of Pennsylvania, have invented a new, original, and ornamental Design for a Jar, of which the following is a specification, reference being had to the accompanying drawing, forming a part thereof.

Figure 1 is a face view of a jar embodying my new design; Fig. 2 is a side view thereof, and Fig. 3 is an inverted plan view, partly in section, of the jar of Fig. 1.

I claim:

The ornamental design for a jar, as shown.

OLBERT C. NOBLE.
